UNITED STATES PATENT OFFICE

150,640

DESIGN FOR A FRONT PANEL FOR MUSIC BOXES OR CABINETS

Robert P. Miller, Ann Arbor, Mich.

Application January 9, 1947, Serial No. 136,015

Term of patent 3½ years

(CL. D56—4)

To all whom it may concern:

Be it known that I, Robert P. Miller, a citizen of the United States, residing at Ann Arbor, in the county of Washtenaw and State of Michigan, have invented a new, original, and ornamental Design for a Front Panel for Music Boxes or Cabinets, of which the following is a specification, reference being had to the accompanying drawing, forming part thereof, in which:

Fig. 1 is a front view, and

Fig. 2 is a side elevational view of a front panel for music boxes or cabinets, showing my new design.

The dotted lines in Fig. 2 of the drawing are for illustrative purposes only.

I claim:

The ornamental design for a front panel for music boxes or cabinets, as shown and described.

ROBERT P. MILLER.
